ILLINOIS

TOUCH-UP SPRAY GUN

Application filed July 18, 1929. Serial No. 379,089.

Our invention relates to appliances for spraying paints or other liquids in relatively small quantities, for which purpose it is customary to mount the needed spray appliance on a liquid container (or so-called "paint cup"), so that this container is supported from the spray appliances held in a hand of the user.

Since the needed liquid container is desirably connected to a relatively forward portion of the spray appliance, so as to reduce the length of the liquid passages in which residual paint or other material may dry when the appliance is not in use, the weight of this container and of its contents are unbalanced with respect to the hand of the user if the spray appliance is of a pistol-shaped or so-called "spray gun" type having a handle at its rear end. Moreover, the size required for such a rear handle in order that it may conveniently be grasped by the hand of a workman is such as to add considerable weight to the spray appliance and container assembly.

In one of its objects, our invention aims to overcome these objections by providing a spray appliance adapted to support a liquid container and designed so as that it can conveniently be held in a hand of the user, although not provided with a special handle for this purpose. Furthermore, our invention aims to provide a spray appliance arrangement which will cause the entire assemblage (namely, the spray appliance, the attached liquid container and the portion of the air hose supported by the appliance) to be substantially balanced in the hand of the user.

Still further and also more detailed objects of our invention will appear from the following specification and from the accompanying drawings, in which drawings

Fig. 1 is a side elevation of a spray gun embodying our invention, with dotted lines showing a hand holding the same.

Fig. 2 is an enlarged central, vertical and longitudinal section through the same embodiment, with some portions shown in side elevation.

Fig. 3 is an enlargement of a portion of the body casting as originally bored.

Fig. 4 is an enlarged bottom view of the air valve body.

Figs. 5 and 6 are sections taken respectively along the lines 5-5 and 6-6 of Fig. 4.

Fig. 7 is a section taken along the line 7-7 of Fig. 2.

Another difficulty encountered with spray appliances of this class, and particularly with the miniature types designed for touching up imperfectly coated spots on surfaces to which a coating has been applied by means of large sized spray gun, is the difficulty of accurately forming the needed air and liquid passages in the body of a cast appliance by means of cores. In practice, the small diameter cores needed for this purpose are apt to be damaged in handling and also are often damaged by the rush of the molten metal into the mold, thereby clogging the passages and forming blow holes in the casting, thus causing a waste of castings and of the labor spent in machining these castings to the state in which they can be tested. Our present invention aims to overcome these difficulties by providing a spray appliance in which those portions of the needed liquid and air passages which are needed in the cast body consist of bores drilled in the initially solid casting, so that no coring of the casting is required and so that the appliance body can have thinner walls around such passages than would be needed if the passages were cored.

Furthermore, our invention aims to provide an unusually compact disposition of the operating parts which permits a decided reduction in the weight of such a spray appliance, which disposes the control lever in convenient position for easy and sensitive operation by the hand which holds the entire assembly, and which causes an actuating movement of the control lever to open the air valve more rapidly than the liquid valve.

In the illustrated embodiment, the body of our spraying appliance (which desirably is cast of aluminum) includes a forward head 1; a neck 2 extending rearwardly from the head; and a substantially rectangular upright frame which has its forward vertical member 100

3 formed by the rear portion of the neck and connected by upper and lower frame members 4 and 5 to the rear frame member 6; a tail 7 projecting rearwardly from the lower 5 rear corner of the frame, a rigid arm 8 projecting downward from the lower frame member 5 intermediate of the ends of the latter; and a ring 9 upon the rear portion of the upper frame member 4.

10 Three longitudinal bores are formed in this initially solid casting from its front; namely an upper neck bore 10 extending from the front of the head to the interior of the said frame, a lower neck bore 11 terminating 15 forwardly of the frame opening, and a bore 12 extending through the forward frame member 3 and longitudinally through the lower frame member 5 to the juncture of the latter with the tail 7. This tail desirably 20 extends oblique to the lower frame member and has a longitudinal bore 13 extending into it from its rear end and intercepting the lowest longitudinal bore 12, while a bore 14 extends upward in the forward frame 25 member and connects the longitudinal bores 10 and 12. This vertical bore 14 is crossed by the bore 12 and the part of the bore 12 forward of the said vertical bore is afterwards sealed by a metal plug 15.

30 After forming the above named bores in the casting, this casting is suitably threaded for screwing a liquid nozzle 16 into the forward end of the upper longitudinal bore 10, a stem guide 17 into the rear end of the same bore, and a retainer ring 18 on the head 1 of the casting. This retainer ring overhangs the rear end of a collar 19 which fits upon the rearwardly tapering exterior of a suitably perforated air nozzle 20 socketed 40 upon the liquid nozzle 16, thereby affording a spray head construction.

45 The (forward) outlet of the tubular liquid nozzle 16 is controlled by a needle valve having a cylindrical stem 21 which extends slidably through the guide 17 and through a packing 22 within a cover 23 screwed upon this guide, and this stem also extends through a thrust member 24 projecting from the rear frame member 6. The thrust member 24 is 50 threaded into a bore 25 formed in alignment with the upper bore 10 in the neck. A compression spring 26 has its rear end engaging the thrust member and its forward end engaging a cup 27 pinned (or otherwise fastened) to the needle valve stem 21, which cup slides in the threaded bore 25.

60 The upper portion of the vertical bore 14 (namely the part 14 A adjacent to the upper bore 10) is contracted in diameter to afford a stop shoulder 28 (Fig. 3) for limiting the upward insertion of a liquid tube 34, which tube 34 extends into the said vertical bore and has its lower end portion 33 threaded for attaching a nipple 30 supporting the upper end 65 of the usual riser pipe 31 of a paint cup 32.

The intermediate part 34 of the liquid tube which is opposite to and between the bores 11 and 12 is contracted in outside diameter to a size considerably smaller than the diameter of the bore 14, thereby affording a tubular space connecting the air passage bores 12 and 11.

70 The bore 13 in the oblique tail preferably has its forward portion reduced in diameter to fit the forward cylindrical portion 35 of an air valve body which valve has its main portion 36 fitting the bore 13, and the rear end of the tail has an exterior thread 37 for attaching an air hose, which hose 38 is shown diagrammatically in dotted lines in Fig. 1.

75 The air valve body has a main bore portion 39 in its larger diameter main portion 36, as shown in Fig. 5, and this bore portion 39 being continued by a smaller diametered 80 guide bore 40 in which the stem 41 of an air valve member is slidable, and the stem 41 is fast on a head 42 formed for seating on the rear end of the air valve body. A compression spring 43 is interposed between this air valve head 42 and an adjustable tubular stop 44 threaded into the rear end of the tail, so that this spring continually tends to close the air valve.

85 Pivotedly mounted on the upper frame member 4 on a horizontal axis, as on the stem of a screw 45, is a bell-crank lever including a depending lever arm 46 which extends downward in front of the forward end of the air valve stem 41, and also including an actuating arm 47 extending forward and desirably having a fingerpiece 48 formed on its forward end. The lever arm 46 has a perforation 49 (Fig. 7) through which the needle valve stem (or liquid valve stem) 21 90 extends, this perforation being of such a size with respect to the said valve stem as to permit limited rocking movement of the bell-crank lever about the said pivoting screw.

95 The portion of the depending lever arm 46 adjacent to its said perforation 49 is disposed for engaging the cup 27 (which is fastened to the liquid valve stem by a pin 47) when the lever is rocked (in a direction which would be counterclockwise in Figs. 1 and 2) 100 by depressing the fingerpiece 50 on the lever; and the fastening of the cup 27 to the stem 21 (as by the pin 47) is so disposed that the lever, when pressed by the spring 43 through the air valve stem 41 until the bore wall of the lever engages the stem as shown in Fig. 2, is spaced somewhat forwardly from the said cup 27.

105 With the parts thus arranged and assembled, our spray appliance (together with the liquid container 32 and the forward portion of the air hose 38) can readily be supported by a single hand of the user, as for example in the position shown in Fig. 1. In this position, the downwardly directed arm 8 on the 110

body of the appliance extends between the base of the thumb and the base of the forefinger, while the tail 7 overhangs the upwardly turned inner side of the hand, thus permitting the appliance to be held firmly with a light grip by other fingers around the lower portion of the forward frame end and also allowing the tip 50 of the forefinger to rest upon the fingerpiece 48.

When this finger tip is depressed slightly, it rocks the lever against the resistance of the compression spring 43, thereby opening the air valve first, so as to admit air through the bore of the tail piece into the main bore portion 39 of the air valve body, and thence through a bottom slot 51 in this valve body into the lowest longitudinal bore 12. From the bore 12, the air passes through the tubular space between the reduced part 34 of the liquid tube and the vertical bore 14 to the lower bore 11 in the neck and into the head chamber 52 behind the air nozzle 20, thereby supplying air through ports 53 in this air nozzle to the annular air outlet port 54 between the tip of the liquid nozzle 16 and a central port into which this tip extends.

The resulting forwardly directed annular jet of air produces a suction at the (forward) outlet of the liquid nozzle, and as soon as the lever is rocked further, so that its depending arm 46 engages the cup 27 and retracts the needle valve stem 21 this suction causes liquid to be drawn from the container through the liquid tube 33 and the upper longitudinal bore 10 to the bore of the liquid nozzle.

By disposing the parts of our appliance so that the tip of a finger can easily manipulate the lever when the appliance is even lightly grasped by the hand of the user, I enable the user to control the valves with a high degree of delicacy, thereby enabling him to project the paint or other liquid in sprays ranging from quite minute diameters to larger spreads. Consequently, the user can readily effect a highly exact spotting or touching up of parts which need the same. Moreover, since the air valve stem is further from the pivot of the lever than the needle valve stem, the actuation of the lever moves the air valve stem faster than the liquid valve stem, thus making it easier to proportion the supply of air to that of the liquid.

Furthermore, it will be seen from Fig. 1, that the hand grip for which our appliance is designed places the liquid container forwardly of the rear frame portion 6 which overhangs the hand, while the air hose 38 extends rearwardly beyond the hand. By suitably locating the downwardly directed hand-engaging arm 8 with respect to the connections for the liquid container and the air hose connection, we cause the container and the hand-supported part of the hose substantially to counterbalance each other, so that our appliance is approximately balanced when

held as above described. Consequently, a quite light and non-fatiguing grip of the user's hand suffices, and the convenient disposition of the fingerpiece also prevents a tiring of the user.

In assembling our appliance, we desirably apply a film of solder to the upper end of the liquid tube 33 before inserting the latter in the vertical bore and threading it up against the stop shoulder 28. We also desirably apply a film of solder to the stop shoulder 54 on the air valve body (namely, the annular shoulder 54 connecting the two differently sized parts of this air valve body) before inserting the latter in the tail bore 13.

Then we heat the appliance body 2, after the liquid tube and the air valve body have been inserted with solder thus applied to each, to a temperature above the melting point of the solder, so as to solder each of these inserted parts to the shoulders which limit their insertion. By thus proceeding, we prevent an unscrewing of the liquid tube during a detaching of the liquid container, and also support the air valve body in a position in which the slot 51 affords an ample passage leading to the lowest bore 12.

By avoiding all coring of the appliance body, we not only avoid a clogging of passages by broken cores and holes in walls of the casting, but also are able to use considerably thinner walls around the bores, thereby lightening the appliance, which is highly desirable. By extending the air valve stem into the frame opening through which the liquid valve stem 21 extends, we permit a single and short lever arm to control both valves, thereby further reducing the size and weight of the body of our appliance.

However, this lightening of our appliance and our use of accurately machined bores does not interfere with our providing needed adjustments, as the pressures of the springs 26 and 43 can easily be adjusted by merely rotating the thrust members 24 and the 44 respectively. Nor does our construction interfere with an easy cleaning of the passages. An unscrewing of the retaining ring 18 and the liquid nozzle 16 permits a ready cleaning of the upper bore 10, and a detaching of the container-supporting nipple 5 allows the entire liquid passage to be flushed with a solvent for removing any dried material. Likewise a removal of the thrust member 44 permits the spring 43 and the air valve stem 120 to be dropped out of the tail, after which solvent can readily be run through the entire air passages.

What is more, the thin-walled tubular portions which permitted our use of drilled bores cooperate with the disposition of the frame in the spray gun body to afford a frame of quite small thickness transversely of my appliance, thereby exposing the packing cap 23 for convenient adjustment.

However, while we have described our invention in an embodiment including numerous desirable details of construction and arrangements and including a certain type of spray head, we do not wish to be limited in these respects, since changes may be made without departing either from the spirit of our invention or from the appended claims. Nor do we wish to be limited to the employment of novel features of our invention in an appliance supporting a liquid container and one which feeds the liquid with a siphoning action, although we have found it particularly suitable for that class of spray appliances.

We claim as our invention:

1. A spray appliance body comprising an upright frame including end members and longitudinal members, a neck extending forwardly from the forward end frame member above the bottom of the latter, and a tail extending from the lower portion of the rear end member of the frame; the body having a rear bore extending through the said tail and through an adjacent member of the frame into the space bordered by the frame members, a lower bore extending upwardly into the forward end member, and a longitudinal passage extending within the lower longitudinal frame member and connecting the rear bore with the lower bore; the neck having a passage leading from the said longitudinal passage to the forward end of the neck.
2. A spray appliance body as per claim 1, in which the forward end member of the frame has a continuation bore aligning with the longitudinal passage extending forwardly from the lower bore through the said forward end member, in combination with means normally closing the said continuation bore.
3. A spray appliance comprising a body including a neck, a rear end member, two vertically spaced longitudinal members connecting the neck with the rear end member, and a tail projecting rearwardly from the rear end member, the tail having a bore extending forwardly through it into the space between the two longitudinal members; in combination with a tubular valve body shorter than the said tail bore and mounted in the forward end of the latter, the valve body having the rear end of its bore opening into the rear portion of the tail bore, the valve body having a lateral aperture connecting its bore with the said longitudinal passage.
4. In a spray appliance, a body member including a neck, a rear end member, two vertically spaced longitudinal members connecting the neck with the rear end member, a tail extending rearwardly from the rear end member in oblique continuation of the lower longitudinal member, and a rigid holding arm projecting downwardly from the rear end member forwardly of the tail; a valve

stem extending parallel to the said longitudinal members from the neck into the space between the two longitudinal members, a second valve stem extending forwardly from the tail into the said space and oblique to the first valve stem; and a lever pivoted upon the upper longitudinal member for moving both of the valve stems rearwardly; the lever having a forwardly extending actuating arm disposed within reach of a finger of a hand grasping the lower longitudinal member, when the said arm is resting against the juncture of the thumb and forefinger of that hand.

5. A spray appliance as per claim 4, including a suspending eye rising from the rear end member.

6. A spray appliance as per claim 4, in which the lever includes a second arm having a bore through which the first named valve stem extends, the bore being of such a diameter that a wall thereof will engage the first named valve stem to limit the movement of the lever in one direction.

Signed at Chicago, Illinois, July 10th, 1929.
